ABSTRACT OF THE DISCLOSURE

An automatic flash point testing device having a heating chamber for receiving a continuous liquid sample stream and including an electrically powered cartridge heater for heating the sample. A stainless spiral is mounted on the outside of the cartridge heater to produce turbulence in the liquid sample. The liquid sample passes upwardly around the cartridge heater and into a passageway where it is mixed with incoming air. The resulting mixture is passed upwardly into a flash chamber where an air-vapor mixture passes upwardly between a pair of sparking electrodes. When the mixture becomes rich enough to be ignited by the sparks, a flash occurs within the flash chamber, and is detected by a differential thermocouple arrangement, which produces an output signal applied to a magnetic amplifier. The magnetic amplifier in turn produces a control signal which stops a series of heating mode functions in an automatic control system, and initiates a plurality of cooling mode functions. The cooling mode functions are continued for a timed cooling period, after which another heating period is automatically started. The heating mode functions include a continuous increase in power to the cartridge heater by means of a motor-driven variable transformer, a continuous spark generator controlled by a pulse generator, the energization of a heating signal lamp, and the energization of the heating coil for the cartridge heater. The cooling mode functions include the timing of a pre-selected cooling period, the diversion of the continuous liquid sample stream from the liquid feed line to the air feed line for rapid cooling of the flash chamber and the thermocouple therein, the production of a negative D-C signal which drives the temperature recorder downscale to prevent overshoot and clearly indicate the flash point on the temperature record, the actuation of a second motor in the variable transformer to reverse the movement of the sliding contact therein, and energization of a cooling signal lamp.

The present invention relates generally to automatic flash point testing devices and, more particularly, to an improved automatic flash point testing device of the type that is capable of receiving a continuous liquid sample and maintaining a continuous record of the sample temperature and the flash points detected for the sample.

It is a primary object of the present invention to provide an improved flash point testing device which is capable of automatically determining the flash point of a liquid sample with a high degree of accuracy without the necessity of a preliminary estimate of the flash point to be determined. In this connection, another important objective of this invention is to provide such a device which is capable of automatically detecting flash points occurring over a wide temperature range without any preliminary setting for different samples.

Another object of the present invention is to provide an automatic flash point testing device of the foregoing type which greatly reduces the possibility of missing the flash point of any given sample, even where the flash point

2

of the sample is completely unknown before it is tested. A related object is to provide such a device which reliably determines the flash point of a liquid sample in a single test, so that the test does not have to be repeated for any given sample, thereby reducing the overall testing time required for a large number of samples.

It is a further object of the invention to provide an improved automatic flash point testing device of the type described above which eliminates or at least reduces decomposition of the liquid, and the resultant fouling. Thus, it is an object to provide such a device which requires little maintenance with attendant reductions in instrument down time, and increased efficiency.

Still another object of the present invention is to provide an improved automatic flash point testing device which achieves rapid cooling between successive heating periods without a supplementary cooling system.

Yet another object of this invention is to provide an automatic flash point testing instrument of the type described above which includes improved limiting or safety features to prevent overheating and to reduce testing time.

A still further object of the invention is to provide such an improved automatic flash point testing device which permits different timed cooling periods to be selected for different samples or groups of samples.

It is another object of this invention to provide an improved automatic flash point testing device which prevents overshoots on the temperature record so as to provide a clear and accurate record of the detected flash points.

Other objects and advantages of the invention will become apparent upon reading the following detailed description and upon reference to the drawings, in which:

FIG. 1 is a diagrammatic illustration of an automatic flash point testing instrument embodying the present invention with the structure forming the flash test chamber being shown in vertical section;

FIG. 2 is an elevation view, partially in section, of an actual flash point testing instrument embodying the system illustrated in FIG. 1;

FIG. 3 is an enlarged vertical section taken along line 3—3 in FIG. 2; and

FIG. 4 is a schematic circuit diagram of the electrical control system included in the instrument of FIGS. 1 through 3.

While the invention will be described in connection with certain preferred embodiments, it will be understood that it is not intended to limit the invention to these particular embodiments. On the contrary, it is intended to cover all alternatives, modifications, and equivalents as may be included within the spirit and scope of the invention as defined by the appended claims.

Turning now to the drawings and referring first to FIGS. 1 and 3, the liquid sample to be tested is introduced into the instrument through a supply line 10 which includes a pressure regulating valve 11. In a typical operation, the liquid sample is fed at a rate of about 50 ml./minute and at a temperature at least 30° F. below its flash point. During the heating period of each test cycle, the liquid sample flows through a three-way solenoid-operated control valve 12 into the lower end of a heating chamber 13 formed by a cylindrical casing 14. A stainless steel well 15, into which is inserted a cartridge heater 15b, is mounted concentrically within the casing 14 to form an annular chamber through which the liquid sample passes as it is heated. A stainless steel spiral 15a is fixed to the outer surface of the well to provide turbulence, prevent channelling of the liquid and to promote heat transfer. At the top of the heating chamber 13, the liquid sample exits through a longitudinal passageway 14a formed in the upper end of the casing 14 for discharging the sample into a flash chamber 16 formed by a second casing 17

mounted on the upper end of the lower casing 14. To prevent splashing of the liquid sample as it is discharged into the flash chamber 16 and thereby prevent sample droplets from being carried into the vapor space of the test chamber, a perforated splash guard 18 is mounted directly over the upper end of the passageway 14a, the top of the splash guard 18 being closed by a cap 19.

As the heated liquid sample passes through the longitudinal passageway 14a on its way to the flash chamber, it is mixed with air introduced into the passageway 14a from a supply line 20 including a pressure regulating valve 21. In a typical operation, the air is fed into the sample stream between the heater and the flash chamber at a rate of 600 ml./minute. The air supplied to the passageway 14a through the supply line 20 mixes with the liquid sample and passes upwardly through the passageway 14a into the flash chamber 16 and is finally exhausted from the top of the flash chamber through a vapor exhaust line 22. The liquid portion of the sample entering the flash chamber 16 runs to the bottom of the chamber and is drained out through a liquid drain line 23 connected to a conventional flame arrester 23a. As the temperature of the liquid sample is increased, more and more of the sample is converted to the vapor phase and rises to the top of the flash chamber 16 along with the air. Consequently, as the sample heating continues, the air-vapor mixture rising upwardly through the flash chamber 16 becomes richer and richer until it eventually reaches its flash point.

In order to test the liquid sample for its flash point, a pair of spaced electrodes 24 and 25 are provided within the flash chamber 16 and are connected to an electrical sparking system which causes repetitive high voltage sparking between the two electrodes 24, 25. A typical sparking frequency, for example, is one spark per second. Thus, as soon as the air-vapor mixture within the flash chamber reaches its flash point, a minor explosion occurs within the flash chamber, producing a small flame slightly below the electrodes 24, 25. The temperature of the liquid sample is continuously sensed and recorded by an automatic control system including a recorder 26, a measurement control unit 27, and a flash point control unit 28, which also control the cyclic heating, cooling, sparking, and other functions which must be repeated for each test cycle.

Turning now to the schematic circuit diagram in FIG. 4 for a more detailed understanding of the automatic control system in the illustrative instrument, the operator turns the instrument on manually by closing a main on-off switch 30. As will be apparent from the ensuing description, this is the only manual operation required by this instrument, except when it is desired to adjust the automatically timed cooling period to be discussed below. Closing of the switch 30 supplies power from lines L1, L2 to energize a relay K1, thereby throwing poles P1 and P2 to their closed positions to shunt the switch 30 and supply power from lines L1, L2 to the rest of the control system. When the instrument is subsequently turned off by throwing the switch 30 to the off position, the relay K1 is immediately de-energized so as to throw the poles P1 and P2 to their normal open positions to remove power from the entire control system.

As soon as the instrument is turned on, the heating coil HC1 of a space heater 32 (FIG. 2) mounted on the inside wall of the instrument housing is energized to warm up the interior of the instrument. The temperature maintained within the instrument housing by the space heater 32 is controlled by a thermostat TS1 connected in series with the space heater coil HC1.

Turning on the instrument also supplies power to the primary winding T1a of a transformer T1, so that the secondary winding T1b thereof supplies power to a magnetic amplifier 33. The purpose of the magnetic amplifier 33, which is normally turned off, is to produce a predetermined output signal in response to a triggering input signal produced by the occurrence of a flash, as will be

described in more detail below. It has been found that the use of a magnetic amplifier assures reliable detection of the flashes, even over long operating periods. A plurality of diodes D1 through D5 are connected to the amplifier coils in the conventional manner to rectify the A-C power input from the transformer T1 (D1, D2, D4, D5), as well as the amplifier output signal (D3).

In accordance with one important aspect of the present invention, the electric sample heater is operatively associated with an automatic control means which automatically increases the power input to the heater at a controlled rate until the flash point of the sample is reached, at which time the power to the heater is automatically cut off until the next test cycle is initiated. Thus, in the illustrative control system of FIG. 4, closing the on-off switch 30 supplies power to the cartridge heater coil HC2 connected in series with a motor-driven variable transformer 34 which automatically increases the power input to the coil HC2 until a flash point is detected, or simulated by a limiting or safety feature to be described below. During the heating period at the beginning of each test cycle, the sliding contact on the coil 35 of the transformer is advanced at a constant rate designed to increase the sample temperature at a substantially constant rate, i.e., so that the sample temperature profile is substantially linear.

The automatic advancing movement of the sliding contact on the coil 35 is controlled by a heating mode motor M1 which is energized via a series arrangement of (1) a normally closed cam-controlled switch CS1, (2) a pole P6 of a fast-acting triple pole, double throw relay K3, the pole P6 being in its normal position against contact P6b, and (3) a normally closed pole P7 of a time delay relay TD1. Thus, the heating mode motor M1 is operatively connected across the power lines L1, L2 as long as switch CS1 and pole P7 remain closed and pole P6 remains in contact with P6b. This mode of operation continues throughout the heating period, continuously increasing the sample temperature until a flash point is detected or simulated, at which time the sample heating is promptly terminated and a timed cooling period is initiated by automatic control means to be described below.

The automatically varying power input provided by the improved control system of this invention represents a significant improvement in the art of automatic flash point testing instruments. When the power input to the sample heater is fixed at a preselected value, as in certain prior art devices, the sample temperature may rise quite rapidly at first, but the temperature profile gradually flattens out and tends to approach a horizontal line as the flash point is approached. Such systems are perfectly acceptable in applications where the flash point of the sample being tested can be accurately estimated in advance, but serious shortcomings may be encountered when accurate estimates cannot be made. Thus, if the actual flash point of the sample is higher than expected, for example, the temperature curve may level off below the true flash point, with the result that considerable time is wasted before it is discovered that the flash point has not been achieved and the test must be re-run after making suitable adjustment of the fixed power input to the heater. Similarly, if the flash point is lower than expected, the temperature may be rising at such a rapid rate at the true flash point that it cannot be detected, and again the test must be repeated at a different setting after it is discovered that the flash point has been missed.

With the improved control system provided by this invention, the power input to the sample heater is continuously increased at a controlled rate, so that the temperature profile is substantially linear. Thus, the sample temperature increases at a somewhat slower rate, compared with the prior art systems, at the beginning of the heating period, and continues to increase substantially at that same rate until the flash point is reached. Consequently, it is not necessary to estimate the flash point, because it can

be detected with the same degree of accuracy wherever it occurs. More particularly, the flash point will not be missed in the early portion of the heating period due to an excessive rate of temperature increase, nor will it fail to be achieved in the latter portion of the heating period due to a flattening out of the temperature profile; the temperature continues to increase at about the same rate until the flash point is reached.

Since the improved control system of this invention tailors the power input to the sample heater to meet the actual heat requirements of the sample being heated, there is never a wide temperature differential between the sample and the heater. As a result, heat build-up on the surface of the heater is avoided, thereby avoiding decomposition of the liquid sample and the resultant fouling that is often encountered in automatic flash point testers. Moreover, all these advantages are attained with a completely automatic system, and with no chance of over-heating due to the automatic limiting or safety features described below.

For the purpose of indicating to the instrument operator when the instrument is in the heating mode, a "heating" indicator lamp HL, mounted on the front panel of the instrument, is connected in parallel with the serially connected cartridge heater coil HC2 and transformer coil 35 so that the lamp HL is energized and de-energized along with the coil HC2. That is, when the instrument is in the heating mode with the cartridge heater coil HC2 energized, the "heating" lamp HL is turned on, and when the instrument is in any other mode of operation, the "heating" lamp HL is turned off.

To provide intermittent high voltage sparking between the two electrodes 24, 25 within the flash chamber throughout each heating period (i.e., as long as the cartridge heater coil HC2, motor M1, and lamp HL are energized), a series arrangement of a pulse generator 40 and the primary winding T3a of the step-up transformer T3, is also connected in parallel with the serially connected cartridge heater coil HC2 and the transformer coil 35. Consequently, as long as the pole P6 of relay K3 and pole P7 of relay TD1 remain in their normal positions, pulses from the generator 40 are transmitted through the transformer winding T3a, thereby generating corresponding stepped-up pulses in the secondary winding T3b for application to the electrode pair 24, 25 to produce the desired sparks. The sparking rate is thus accurately controlled by the rate of the output pulses from generator 40, which reliably generates pulses at a precise preselected frequency rate over long operating periods.

In order to provide a continuous record of the temperature of the liquid sample, and the flash points as they occur, the continuous temperature recorder 26 (FIG. 1) is operatively connected via terminals 41 and 42 to thermocouple TCL as shown in each of FIGS. 1 through 4. Thermocouple TCL senses the temperature of the liquid sample in the passageway 14a (FIG. 1) and will be referred to hereinafter as the "liquid" thermocouple. A second thermocouple TCV senses the temperature of the vapor in the flash chamber 16, and will be referred to as the "vapor" thermocouple.

The vapor thermocouple TCV, which is connected to input winding LA1 of the magnetic amplifier 33, is very sensitive, responding substantially instantaneously to the sharp increase in temperature that accompanies the flash or flame ignited by the electrodes 24 and 25. Immediately upon the occurrence of such a flash, therefore, the temperature of the vapor thermocouple TCV typically rises quickly about 200° F., applying an input pulse to the winding LA1 of magnetic amplifier 33. This input pulse turns the amplifier 33 on, producing an amplified output pulse which automatically initiates the following operations:

- (1) Diversion of liquid sample stream to air feed line for rapid cooling of flash chamber.

- (2) Driving temperature recorder in a downscale direction.
- (3) Reversal of the movement of the sliding contact on the variable transformer.
- (4) Termination of sample heating.
- (5) Termination of sparking.
- (6) Turning off "heating" indicator lamp and turning on "cooling" indicator lamp.
- (7) Initiation of a preselected timed cooling period, and automatic termination of said cooling period and initiation of another heating period.

Returning to FIG. 4 for a more detailed description of the particular circuitry for carrying out the above functions, the output pulse produced by the amplifier 33 in response to the triggering input from the vapor thermocouple TCV, energizes a mercury relay K2 to throw a normally open pole P3 to its closed position. The closing of the pole P3 immediately energizes the fast-acting relay K3, thereby switching associated pole P6 from contact P6b to P6a to lock the relay K3 into the circuit via pole P7. It will be recognized that pole P3 remains closed only for the duration of the energizing pulse output from the amplifier 33; to insure that the pulse width is sufficient to hold the pole P3 closed long enough to permit switching of the pole P6 to lock the relay K3 into the circuit, a capacitor 36 is connected across the coil of relay K2. This capacitor 36 serves to stretch the output pulse from the amplifier 33 to hold the pole P3 closed for the desired time.

In accordance with a further aspect of this invention, automatic control means are operatively associated with the liquid and air feed lines and the flash detection system for switching the continuous stream of liquid sample from the sample feed line to the air feed line in response to the detection of a flash so as to effect rapid cooling of the flash chamber before initiation of another test cycle. Thus, when the pole P6 is switched to contact P6a, it energizes the solenoid 12a of the three-way solenoid valve 12 (FIG. 1) to turn the valve 90° clockwise from the position shown in FIG. 1, thereby diverting the continuous stream of liquid sample from the normal feed line leading into the heating chamber 13, to the air feed line 20 leading into the passageway 14a connecting the heating chamber 13 and the flash chamber 16. The liquid entering the passageway 14a through the air line 20 initially runs down into the heating chamber 13 until that chamber is filled, after which the relatively cool incoming liquid passes upwardly through the passageway 14a into the flash chamber 16. This provides rapid cooling of the flash chamber 16 and the vapor thermocouple therein, with the cooling liquid being continuously drained out the bottom of the flash chamber via drain line 23.

As another aspect of this invention, automatic control means are operatively associated with the continuous temperature recorder and the flash detection system to apply an overriding D-C signal to the recorder input in response to the detection of a flash so as to drive the recorder pen downscale and prevent overshoot, thereby providing a clear and accurate indication of each detected flash. Thus, the energization of relay K3 in response to a detected flash throws pole P5 to its closed position, thereby applying a negative D-C signal to the positive terminal 41 of the recorder 26 and a corresponding positive D-C signal to the negative terminal 42 to override the thermocouple signal and drive the recorder pen downscale and prevent overshoot. The overriding D-C signal is obtained by converting the A-C signal from a transformer T2 to a D-C signal in a conventional A-C-to-D-C converter 43. Due to the fast action of the relay K3, the overriding D-C signal is applied to the recorder input immediately upon detection of a flash, so that the resulting temperature recorder has a clear and accurate indication of each flash point. The resulting temperature record is typically a saw-toothed curve with the upper peak of each tooth representing a flash point.

During the cooling period, i.e., while the sample stream is being fed through the normal air feed line, the cartridge heater coil HC2, the heating mode motor M1, the "heating" lamp HL, and the pulse generator 40 (the active heating mode elements) are all turned off by the open circuit at relay contact P6b, due to the switching of pole P6. During this same period, the circuit completed by the contact P6a and pole P6 (1) energizes a "cooling" lamp CL, which is mounted on the front instrument panel to indicate that the instrument is operating in the cooling mode, and (2) reverses the movement of the sliding contact on the coil 35 by energizing a cooling mode motor M2. The motor M2 continues the reversed movement of the sliding contact throughout the cooling period, so the extent to which the contact is returned is, in effect, a function of the length of the cooling period, since the motor speed is normally fixed.

In order to time the cooling period, and automatically initiate another heating period at the end of the cooling period, the time delay relay TD1 is energized simultaneously with the energization of the relay K3. The time required for this relay TD1 to actuate the pole P7 associated therewith can be adjusted by a variable resistor R3 connected to the relay coil. A normal cooling cycle is about two minutes, but the variable resistor R3 typically permits the cooling period to be set anywhere between 0.5 and 5 minutes.

At the end of the timed cooling period measured by the time delay relay TD1, the relay automatically throws the normally closed pole P7 associated therewith to its open position. This immediately de-energizes the relay K3 so that poles P5 and P6 return to their normal positions shown in FIG. 4. As pole P6 returns from contact P6a to P6b, the circuit to the coil of relay TD1 is opened, thereby de-energizing the relay and returning pole P7 to its normal closed position. At this point, the circuit is once again in its original condition and, consequently, another test cycle is automatically initiated, beginning with a heating period as described previously.

To briefly summarize the operations performed during one test cycle in the illustrative instrument, at the start of each test cycle power is supplied to the electric heater to heat the continuous stream of liquid sample passing through the heating chamber. At the same time, the automatic sparking device is actuated to produce repetitive sparks within the flash chamber, the "heating" light is turned on, the "cooling" light is turned off, and the temperature recorder begins to record the sample temperature as indicated by the signal from the liquid thermocouple. These heating mode operations continue until a flash occurs inside the flash chamber, with the power input to the electric heater being continuously increased by the motor-driven variable transformer. As soon as a flash occurs, the power supply to the electric heater is turned off, the variable transformer is automatically returned to its starting position for the next cycle, and the liquid sample stream is diverted to the air feed line for cooling purposes. At the same time, the automatic sparking device is turned off, the "heating" light is turned off, the "cooling" light is turned on, and the temperature recorder is driven down-scale so that each peak on the resulting record is an accurate indication of the detected flash point. These cooling mode operations continue for a preselected time period, after which the instrument is automatically returned to the heating mode for another test cycle.

It will be appreciated at this point that in lined-out operation, the motor driven variable transformer 34 moves back and forth over a fairly constant range, but a sudden change in flash point level quickly results in a new range of travel either higher or lower than the previous range, depending upon the direction of the change in flash point level. If it is desired to shorten or lengthen the range of travel, this can be effected by simply adjusting the timed cooling period by means of the variable resistor K3. Thus, shortening the cooling period will shorten the range of

travel of the variable transformer and, conversely, lengthening the cooling period lengthens the range of travel.

In the illustrative system, the driving motors M1 and M2 for the variable transformer are equipped with associated cams C1 and C2, respectively, which control the corresponding limit switches CS1 and CS2 connected in series with the respective motors M1 and M2. During normal operation of the instrument, the switches CS1 and CS2 remain in their normal closed positions illustrated in FIG. 4. However, if either motor drives the sliding contact on the coil 35 beyond a preselected point, typically about 30% and 115% of input voltage, one of the cams C1 or C2 immediately opens one of the switches CS1 or CS2 to de-energize the operative motor. In other words, the cam-controlled switches provide a mechanically responsive safety feature.

In keeping with the present invention, a heat responsive safety means is also provided, in the form of cartridge heater thermostat TS2 connected in parallel with the pole P3 associated with relay K2. If the casing 14 exceeds a preselected temperature, typically 10° F. above the range of the instrument, the thermostat TS2 closes, thereby simulating a detected flash and initiating the same functions initiated by the closing of the pole P3, as described above.

As can be seen from the foregoing detailed description, this invention provides an improved flash point testing device which automatically determines the flash point of a liquid sample with a high degree of accuracy without the necessity of a preliminary estimate of the flash point to be determined. It has been found that the results obtained by the completely automatic and continuous operation of this instrument agree with results obtained by the Tag Closed Cup Flash Point test method (ASTM Test Method D-56) within plus or minus 2° F., and can be readily correlated with Pensky-Martens Closed Cup Flash Point method (ASTM Test Method D-93). Moreover, the instrument of this invention is capable of automatically detecting flash points occurring over a wide temperature range without any preliminary setting for different samples, and it greatly reduces the possibility of missing the flash point of any given sample, since the temperature is increased steadily at a predetermined rate throughout the test. Consequently, the flash points are determined reliably in a single test, so that any given test does not have to be repeated, thereby reducing the overall testing time required for a large number of samples. Moreover, this instrument eliminates or at least reduces decomposition of the liquid sample within the instrument, thereby eliminating the resultant fouling. The instrument requires little maintenance with attendant reductions in instrument downtime, and increased efficiency. The switching of the liquid sample stream to the air feed line during the cooling period provides rapid cooling of the instrument between successive heating periods, and the manual adjustment provided on the time delay relay permits different timed cooling periods to be selected for different samples or groups of samples, with automatic correlated adjustment in the travel range of the motor-driven variable transformer which controls the heating rate. Finally, the automatically applied negative D-C signal which drives the temperature recorder downscale immediately upon the occurrence of a flash, prevents overshoots on the temperature record and provides a clear and accurate record of the detected flash points.

We claim as our invention:

1. An improved automatic flash point testing instrument comprising the combination of means forming a flash chamber for receiving an air-vapor mixture and including means for igniting said mixture, flash detection means for detecting a flash in said flash chamber due to ignition of said air-vapor mixture, means forming a heating chamber for heating a liquid sample to produce the vapor for said air-vapor mixture, a liquid sample feed line for supplying liquid sample to said heating chamber,

an air feed line for mixing air with the liquid sample between the heating chamber and the flash chamber, valve means interconnecting said liquid sample feed line in said air feed line and automatic control means operatively associated with said valve means and said flash detection means for switching the stream of liquid sample from said sample feed line to said air feed line in response to the detection of a flash so as to effect rapid cooling of the flash chamber prior to initiation of the next test cycle.

2. An improved automatic flash point testing instrument as defined in claim 1 in which said automatic control means includes a solenoid-operated valve operatively associated with said flash detection means.

3. An improved automatic flash point testing instrument as defined in claim 1 which includes heat responsive limiting means for simulating a flash in response to a predetermined temperature of said liquid sample to terminate the heating of said liquid sample.

4. An improved automatic flash point testing instrument as defined in claim 3 wherein said heating chamber includes electric heating means, and said heat responsive limiting means includes sensing means for sensing the temperature of the heated liquid sample, and control means operatively connected to said sensing means and responsive to a preselected sensed temperature for (1) cutting off the power input to said electrical heating means, (2) automatically switching the stream of liquid sample from said sample feed line to said air feed line to effect rapid cooling of the flash chamber prior to initiation of the next test cycle, and (3) automatically turning on the power to said electrical heating means after a timed cooling period to start a new test cycle.

5. An improved flash point testing instrument as defined in claim 1 which includes first control means for carrying out a plurality of heating mode functions and

second control means for carrying out a plurality of cooling mode functions, other than the switching of the liquid sample stream, a flash detection system including a differential thermocouple arrangement for detecting a flash in said flash chamber due to ignition of said air-vapor mixture and producing an output signal in response to the detected flash, and a magnetic amplifier responsive to said output signal for producing a control signal to render simultaneously said first control means inoperative and said second control means operative.

6. An improved flash point testing instrument as defined in claim 1 which includes a continuous temperature recorder including a thermocouple for sensing the increasing temperature of the sample leading up to a detected flash, said thermocouple generating an input signal for said recorder, and automatic control means operatively associated with said recorder and said flash detection means for applying an overriding D-C signal to said recorder in response to the detection of a flash so as to drive the recorder downscale and prevent overshoot, thereby providing a clear and accurate indication of each detected flash.
